ATTEST.

UNITED STATES PATENT OFFICE.

ANTON CZERNICK, OF REGINA, SASKATCHEWAN, CANADA.

GRAIN-STOOKER.

1,282,545.

Specification of Letters Patent. Patented Oct. 22, 1918.

Application filed March 29, 1918. Serial No. 225,590.

To all whom it may concern:

Be it known that I, ANTON CZERNICK, a subject of the King of Great Britain, residing at the city of Regina, Province of Saskatchewan, Dominion of Canada, have invented certain new and useful Improvements in Grain-Stookers, of which the following is a specification.

This invention relates to grain stookers, and the objects of the invention are to facilitate collecting the grain and dumping the same in the form of a shock, to permit of the heads of the sheaves being properly bunched together during the operation of dumping, to simplify the construction of the sheaf receiving means, and generally to adapt the several parts to better perform the functions required of them.

With the above and other objects in view, the invention consists essentially of the improved construction particularly described and set forth in the following specifications and accompanying drawings forming part of the same.

25 The drawings.

Figure 1 is a fragmentary end-elevation of a binder showing the improved sheaf shocking means attached thereto.

30 Fig. 2 is a plan view of the same.

Fig. 3 is a side elevation of the sheaf shock mechanism.

Fig. 4 is a perspective view of the sheaf shocking mechanism.

35 Like characters of reference refer to like parts in the several figures.

Referring to the drawings, A represents a binder of any usual description of the frame of which the sheaf shock mechanism 40 B is operatively attached, the said sheaf shock mechanism being so arranged relative to the binder deck, that the sheaves leaving the same will be deposited in the sheaf receiving and shocking means.

45 The sheaf shocking means B comprises a frame 11 closed on three sides but open to the rear end. This frame rotatably supports a basket 12 of semi-cylindrical formation which is provided on opposite sides with 50 stub crank members 13 the outer ends of which are rotatably supported on said frame.

These crank members are supported by links 14 with rods 15 the outer ends of which are connected to the transversely extending

55 member 16, the said rods being slidably mounted in the frame 11 so that on rotation

of the cranks 13 reciprocating motion is transmitted to the rods 15 and consequently to the member 16.

The member 16 carries a packing element 60 17 which is of unique construction comprising a pair of arms 18 secured to the member 16 and slidably mounted in the frame 11, these arms being arranged in parallel relation and connected by a transversely extending member 19 which is offset intermediate of its length for a purpose to be made clear hereafter. One of the crank members 18 is provided with a sprocket wheel 20 which is connected by the chain 21 with the 70 sprocket wheel 22 mounted on the spindle 23, rotatably supported on the frame 11. This spindle is provided with a crank arm 24 connected to the flexible member 25 which is designed to pass around the pulleys 26 75 and 27 and be connected to the lever 28 located adjacent to the driver's seat 29. The basket 12 is provided on its under face with a pair of bearings 30 rotatably supporting the rod 31, which is provided with an offset 80 crank end 32 carrying a cam roller 33 designed to engage with a curvilinear cam race 34 operatively mounted on the frame 11.

The rod 31 is connected by the link 35 with one of the crank members 13, and this 85 rod is further provided with a pair of arms 36 which normally lie along the under face of the basket 12 and are provided with upturned ends 37 forming fingers designed to engage with the sheaves delivered to the bottom of the basket.

The frame 11 is supported by the ground wheel 38.

The assembly of the several parts will be readily understood from the foregoing description.

When a binder equipped in this manner is in use, the sheaves as they leave the binder deck are delivered to the basket collector 12 and when the desired number of sheaves have been so collected the driver actuates the lever 28 transmitting the motion through the flexible member 25 to the spindle 23. This spindle is thus rotated and transmits its rotary motion through the sprocket 22, 100 chain 21 and sprocket 20 to the crank member 13 thereby rotating the basket collector 12 about two thirds of a revolution so dumping the sheaves collected in the basket in the form of a stool.

110 During the rotation of the basket 12, the member 17 is reciprocated, so that while

dumping the sheaves the heads are bunched together in a manner best calculated to spread the butts of the sheaves and form a proper shock.

5 During the rotation of the basket 12 the rod 31 is also actuated by the cam 33 engaging cam race and by the link 35 connecting the rod with the crank member 13, and as a result of this actuation the fingers 37 are rotated out of engagement with the sheaves in 10 the basket 12 liberating the same and permitting them to be readily dumped.

When the sheaves have been dumped to 15 form a shock, the basket 12 is returned to its normal position preparatory to collecting the number of sheaves necessary to form another shock when the above operation is repeated.

From this description it will be seen that 20 I have invented a sheaf shocker which can be advantageously utilized by farmers, resulting in a considerable saving of time and labor, the said shocking device being capable of being attached to any of the usual binders 25 at present in use.

As many changes could be made in the above construction and many apparently 30 widely different embodiments of my invention, constructed within the scope of the claims, without departing from the spirit or scope thereof, it is intended that all matter contained in the accompanying specification and drawings shall be interpreted as illustrative and not in a limiting sense.

35 What I claim as my invention is:

1. The combination with a binder, of a sheaf receiving basket arranged adjacent to the binder deck, stub crank members rotatably supporting the basket, a packing member at one end of the basket, link and rod mechanism connecting the packing member to the stub crank members, a rod rotatably mounted below the basket, fingers carried by the rod designed to engage the sheaves in the basket, means for rotating the basket, and link means for connecting the last said rod to one of the stub crank members, as and for the purpose specified.

2. The combination with a binder, of a sheaf receiving basket located adjacent to the binder deck, stub crank members rotatably supporting the basket, a packing member at 40 one end of the basket, link and rod mechanism connecting the packing member to the stub crank members, a rod rotatably mounted below the basket, fingers carried by the rod 45 designed to engage the sheaves in the basket, means for rotating the basket, and link means for connecting the last said rod to one of the stub crank members, as and for the purpose specified.

3. The combination with a binder, of a basket, stub crank members rotatably supporting the basket, a packing member at one end of the basket, link and rod mechanism 60 connecting the packing member to the stub crank members, a rod rotatably mounted on the bottom of the basket having a crank end, a cam on the crank end, a curvilinear cam race co-acting with the cam, fingers on the rod below the basket, and means for rotating the basket.

In witness whereof I have hereunto set my hand in the presence of two witnesses.

ANTON CZERNICK.
